US00D981480S

(12) **United States Design Patent** (10) **Patent No.:** **US D981,480 S**
Urabe et al. (45) **Date of Patent:** **** Mar. 21, 2023**

(54) **PRINTER**

(71) Applicant: **OKI ELECTRIC INDUSTRY CO., LTD.**, Tokyo (JP)

(72) Inventors: **Tomoya Urabe**, Tokyo (JP); **Shiro Ino**, Tokyo (JP); **Katsuhiro Yamaguchi**, Tokyo (JP); **Morihiro Saigusa**, Tokyo (JP)

(73) Assignee: **OKI ELECTRIC INDUSTRY CO., LTD.**, Tokyo (JP)

(**) Term: **15 Years**

(21) Appl. No.: **29/736,150**

(22) Filed: **May 28, 2020**

(30) **Foreign Application Priority Data**

Jan. 10, 2020 (JP) ..... 2020000358 D

(57) **CLAIM**

The ornamental design for a printer, as shown and described.

DESCRIPTION

FIG. 1 is a perspective view of top, front, and right side of a printer;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines shown and the areas within the broken lines represent unclaimed subject matter and form no part of the claimed design.

1 Claim, 7 Drawing Sheets
